US0D1105999S

(12) **United States Design Patent** (10) **Patent No.:** **US D1,105,999 S**
(45) **Date of Patent:** **** Dec. 16, 2025**

(54) **VEHICLE GRILLE**

(71) Applicant: **Daimler Truck North America LLC**,
Portland, OR (US)

(72) Inventors: **Steven Powell**, Beaverton, OR (US);
Jeffrey Cotner, Portland, OR (US);
Mauricio Cavalheiro, Portland, OR (US); **Austin Cox**, Portland, OR (US);
Rafael Dos Santos, Portland, OR (US);
Curtis Parker, Portland, OR (US);
Michael Woodruff, Lake Oswego, OR (US); **Daniel Kunzelmann**, Portland, OR (US); **Jackson Slocum**, Portland, OR (US); **Dinesh Madugundi**, Beaverton, OR (US); **Paolo Zanetti**, Portland, OR (US)

(73) Assignee: **Daimler Truck North America LLC**,
Portland, OR (US)

(**) Term: **15 Years**

(21) Appl. No.: **29/945,152**

(22) Filed: **May 31, 2024**

(57) **CLAIM**

The ornamental design for a vehicle grille as shown and described.

DESCRIPTION

FIG. 1 is a front, left, top perspective view of a vehicle grille showing our new design;

FIG. 2 is a front, right, bottom perspective view thereof;

FIG. 3 is a front view thereof;

FIG. 4 is a right side view thereof;

FIG. 5 is a left side view thereof;

FIG. 6 is back view thereof;

(Continued)

FIG. 7 is a top view thereof; and,
FIG. 8 is a bottom view thereof.

The ghosted or low contrasted portions of the vehicle grille illustrate portions that form no part of the claimed design. The dash lines in the figures surround portions of the vehicle grille that form no part of the claimed design. In addition, the dash lines do not form part of the claimed design.

1 Claim, 6 Drawing Sheets
